UNITED STATES PATENT OFFICE.

ROBERT L. MCINTOSH, OF INDIANA HARBOR, INDIANA, ASSIGNOR TO INLAND STEEL COMPANY, OF INDIANA HARBOR, INDIANA, A CORPORATION OF DELAWARE.

HEATING APPARATUS FOR ROLLS.

Application filed May 13, 1922. Serial No. 560,552.

To all whom it may concern:

Be it known that I, ROBERT L. MCINTOSH, a citizen of the United States, residing at Indiana Harbor, in the county of Lake and State of Indiana, have invented a new and useful Improvement in Heating Apparatus for Rolls, of which the following is a specification.

My invention relates, more particularly, to heating apparatus for preheating, by the use of electric current, the rolls of rolling mills, to condition the rolls for rolling relatively wide, narrow gage, sheets, without requiring the rolling of narrow, heavy gage, sheets; and my primary object is to provide a novel and simple construction of electric heating apparatus for the purpose, which will be highly effective in operation and by which the rolls may be preheated, in a comparatively short time, to the desired temperature for rolling wide, narrow gage, sheets and injury to the rolls from foundry strains therein will be reduced to the minimum.

Referring to the accompanying drawings: Figure 1 is a view in front elevation of a rolling mill equipped with means for preliminarily heating the rolls in accordance with my invention. Figure 2 is a section taken at the irregular lines 2—2 on Fig. 1 and viewed in the direction of the arrows. Figure 3 is a broken enlarged sectional view taken at the line 3—3 on Fig. 1 and viewed in the direction of the arrows. Figure 4 is an enlarged plan sectional view taken at the line 4—4 on Fig. 2 and viewed in the direction of the arrows. Figure 5 is a plan sectional view taken at the line 5—5 on Fig. 2 and viewed in the direction of the arrows. Figure 6 is a face view of one of the plurality of electrical heating units forming portions of my improved apparatus, with certain portions thereof broken away to disclose interior details. Figure 7 is a section taken at the line 7—7 on Fig. 6 and viewed in the direction of the arrows; and Figure 8, a section taken at the line 8—8 on Fig. 6 and viewed in the direction of the arrows.

As a premise to the following description it may be stated that my improved apparatus is preferably employed for preliminarily heating the pair of cooperating rolls used for rolling the sheets, throughout their cross-section and substantially throughout the length of the main body portions of the

rolls, preferably to a temperature of about 300° F. at their peripheries at a point midway between their ends thereby to cause the rolls to be conditioned for properly rolling sheets of relatively great width and thin gage.

In the drawings the invention is shown as applied to a rolling mill of common construction and involving generally stated a framework affording the uprights 9 spaced apart in which the necks 10 of the two rolls 11, one of which superposes the other, are journaled, the ends of the rolls 11 being adapted for connection therewith of wabblers through the medium of which these rolls are driven. It may be here stated that according to common practice the lower roll is of true cylindrical form, and the periphery of that portion of the upper roll which is contacted by the sheet-forming bars in the rolling operation, is circumferentially slightly concaved in order that these rolls shall properly function to produce sheets of uniform thickness throughout their extent, after the rolls have become properly heated.

This invention is an improvement on the invention of David P. Thompson which is shown and described in his copending application, Serial No. 560,549, filed on even date with this application, and the construction herein shown and described is therefore claimed in its broader aspects of novelty in that application rather than in the present application.

The particular illustrated embodiment of my invention comprises a housing for application to the pair of rolls, which is provided with a series of electrical heating elements positioned to contact with substantially the entire peripheries of the portions of the rolls between the necks thereof. The housing shown is formed of two similar sections 12 adapted to be applied to the rolls from opposite sides thereof and be secured in place thereon. Each section is shown as formed of the elements 13, 14 and 15 in the form of angle-bars spaced apart lengthwise of the rolls, the upper ends of the elements 13, 14 and 15, as to each section, being connected with a plate 16 and the lower ends with a plate 17, the plates 16 and 17 containing apertures, certain of which open through the margins of the plates, for receiving bolts 18 through the medium of which the housing sections are releasably

secured in position on the rolls. The lower ends of the elements 13 and 15 are provided with legs 19 in which a shaft 20, carrying a roller 21, is mounted, and the upper ends of the elements 13 and 15 are provided with upwardly-extending handle-portions 22. Each of the housing sections 12 also comprises a member, represented at 23, of sheet-like form, this member being preferably of flexible sheet-metal and contoured to substantially conform to the contour of the portions of the peripheries of the rollers which it opposes as shown in Fig. 2. Each member 23 is preferably rigidly secured, as by riveting, or otherwise, to those portions of the angle-shaped elements 13, 14 and 15 which parallel the rolls, at the upper and lower portions of the members 23, but are preferably disconnected from the said elements at those portions thereof between horizontal planes passing through the centers of the rolls.

The electrical heating elements forming a portion of each of the sections 12, and shown as of the common "space-heater" type, are represented at 24. These heating elements which are interposed between the rolls and the members 23, contact with the peripheries of the rolls as represented in Fig. 2 and are grouped in any desirable arrangement, as for example that shown wherein they extend in a direction lengthwise of the rolls and in spaced relation to each other. Each heating element 24 is provided at opposite ends with angle-shaped brackets 25 which extend through openings 23* in the member 23, these brackets serving as terminals for the heating elements and through the medium of which these elements are electrically connected together in series, or in parallel, as desired, and with any suitable source of current supply. In the particular arrangement shown all of the brackets 25 at one end of the heating device are connected with one of the main line current wires and all of the brackets at the other end are connected with the other of the main line current wires.

Each of the heating elements 24 is shown as comprising a metal casing 26, containing a coil of any suitable electrical resistance wire 27 extending substantially the full length of the element and wound about a core 28 of mica, or any other suitable insulating material, there being interposed between the bottom wall 29 of the casing 26 and the coil 27 a sheet 30 of insulating material, as for example mica. A strip of metal 31 directly underlies the upper wall portion 32 of the casing 26 and has interposed between it and the coil 27 a sheet 33 of insulating material as for example mica. Each element 24 is provided at each end with an eyelet 34 which flatwise bears

at a shoulder-portion 35 thereof against the insulating strip 30 and extends through openings in the strips 31 and 33 and cut-out portions 36 in the upper portions 32 of the casing 26, these eyelets also extending through metal washers 37 and through openings in the base portions of the brackets 25. A mica washer 38 extends between each washer 37 and the iron strip 31, and the openings through the strip 31 are such size that the walls thereof are out of contact with the eyelets 34. Each eyelet 34 being in electrical contact with the adjacent bracket 25, is in electrical contact with one of the terminals of the coil 27.

In the particular construction illustrated means are provided whereby the sheet portions 23 may be bent into such form that the heating elements 24 will contact with the peripheries of the rolls throughout substantially their entire extent as shown in Fig. 2, these means comprising a U-bar 39 which extends at its cross-bar portion 40 against the outer surface of the sheet 23 and in a plane parallel with the axes of the rolls, the outer ends of the arms of the yoke 39, and represented at 41, being threaded and extending through openings in a channel-bar 42 secured to, and extending crosswise of, the members 13, 14 and 15, the threaded ends of the arms 41 being provided with pairs of nuts 43 by means of which the desired pressure may be exerted and maintained against the sheeting 23, through the yokes 39 for deforming these sheets into the desired shape as above stated, it being understood that after these sheets have once been deformed by adjusting the yokes 39 as stated to adapt them to rolls of a particular size, no further adjustment is required. In the use of the apparatus shown the sections 12 are applied to opposite sides of the assembled rolls to the position shown in Fig. 2, the provision of the rollers 21 and the handle portions 22 serving to permit these sections to be wheeled to the position for application to the rolls, after the manner of a wheelbarrow. With the sections 12 in place on the rolls and the desired circuit connections made for supplying current to the various heater elements 24, the current is permitted to pass through these elements, the heat generated thereby radiating into the rolls until the rolls are heated to the desired degree, as for example the temperature above specified. It has been found by actual demonstration that the rolls even when of the largest dimensions commonly used in rolling mill practice, may be heated to a degree sufficient for the starting in of the rolling of relatively wide sheets of thin gage, and that such heating may be effected in a relatively short length of time, and thus great economy of structure and in the operation of mills, is effected.

It has also been found in the actual practice of the invention that the heating up of the rolls in accordance with the invention, as explained, almost entirely eliminates the danger of fracturing the rolls during the initial heating up of the same, from foundry strains therein, the heating of the rolls as stated, and which it will be understood involves a relatively gentle application of heat, as compared with the heating of the rolls by forcing heat into the latter from relatively highly heated bars by friction of the bars therewith and by heat radiated therefrom, appearing to produce an action on the rolls in the nature of annealing.

While I have described a certain particular apparatus embodying my invention, I do not wish to be understood as intending to limit it thereto as the same may be variously modified and altered without departing from the spirit of the invention.

What I claim as new, and desire to secure by Letters Patent, is:

1. Apparatus for heating rolls of rolling mills, said apparatus comprising a supporting frame, a sheet like member carried by the frame, electrical heating elements positioned upon the sheet like member, and means for positioning the frame and member carried thereby adjacent the roll to be heated.

2. Apparatus for heating rolls of rolling mills, said apparatus comprising a supporting frame, a sheet like member carried by the frame, electrical heating elements positioned upon the sheet like member, means for positioning the frame and member carried thereby adjacent the roll to be heated and means for adjusting the sheet like members to the roll contour.

3. Apparatus for heating rolls of rolling mills, said apparatus comprising a supporting frame, a sheet like member secured to the frame said member having a convex face toward the frame, and means for flexing the sheet like member to conform substantially to the contour of a roll to be heated.

4. Apparatus for heating rolls of rolling mills, said apparatus comprising a supporting frame, a sheet like member secured to the frame said member having a convex face toward the frame and secured to the frame throughout a portion only of its extent, and means carried by the frame for flexing the sheet like member to conform substantially to the contour of a roll to be heated.

5. Apparatus adapted for heating a rolling mill roll in position in its housing, said apparatus comprising relatively mov-

ably sections adapted to be applied to the roll from opposite sides thereof, each section comprising a supporting frame, sheet like members carried by the frame, electrical heating elements associated with the inner faces of the sheet like members, the sheet like members conforming approximately to the contour of the roll to be heated, and means adapted to secure the sections together upon opposite sides of the roll.

6. Apparatus adapted for heating a pair of rolling mill rolls in position in their housing, said apparatus comprising relatively movable sections adapted to be applied to the rolls from opposite sides thereof, each section comprising a supporting frame, sheet like members carried by the frame, electrical heating elements associated with the inner faces of the sheet like members, the sheet like members conforming approximately to the contour of the rolls to be heated, means adapted to secure the sections together upon opposite sides of the rolls and means adapted to flex the sheet like members to bring them more close to the roll surfaces.

7. Rolling mill apparatus comprising rolls extending side by side, and electric-current-energized heating means located at the peripheries of said rolls and conforming thereto substantially throughout the extent of said peripheries, said means comprising a sheet-like member substantially housing the rolls, and electrical heating elements associated therewith adjacent the peripheries of the rolls for heating the latter.

8. Rolling mill apparatus comprising rolls extending side by side, and electric-current-energized heating means located at the peripheries of said rolls and conforming thereto substantially throughout the extent of said peripheries, said means comprising a sheet-like member substantially housing the rolls, and electrical heating elements associated therewith adjacent the peripheries of the rolls for heating the latter, said elements being located between said sheet-like member and said rolls and contacting with the latter.

9. Heating apparatus for rolls formed of relatively movable sections comprising electric-current-energized heating elements, adapted to be applied to the roll structure from opposite sides thereof, said sections being equipped with rollers adapting said sections to be wheeled into a position to be applied to the roll structure.

ROBERT L. McINTOSH.
